UNITED STATES PATENT OFFICE.

WILLIAM ANDREW ROBERT ANGUS, OF WINNIPEG, MANITOBA, CANADA.

REPAIR-CLAMP.

1,374,174.

Specification of Letters Patent. Patented Apr. 12, 1921.

Application filed March 8, 1920. Serial No. 364,113.

To all whom it may concern:

Be it known that I, WILLIAM ANDREW ROBERT ANGUS, subject of the King of Great Britain, resident of the city of Winnipeg, in 5 the Province of Manitoba, Canada, have invented certain new and useful Improvements in Repair-Clamps, of which the following is the specification.

The invention relates to improvements in 10 repair clamps and particularly to a repair clamp for use in repairing broken rails and the principal object of the invention is to provide a clamp which can be readily placed in position in respect to the rail and which 15 can be quickly tightened up and set to hold a pair of angle irons or fish plates in place on opposite sides of the rail at the break thereby effecting quickly a temporary repair which can be relied upon to safely carry the 20 traffic until a final repair can be made.

A further object is to construct the clamp in a simple, durable and inexpensive manner and so that it can be quickly adjusted and set and as easily removed.

25 With the above more important objects in view, which will become apparent as the description proceeds, the invention consists essentially in the arrangement and construction of parts hereinafter more particularly 30 described and later pointed out in the appended claims, reference being had to the accompanying drawing in which:

Figure 1 is a side view of a pair of my clamps as they appear in use.

35 Fig. 2 is an enlarged detailed sectional view at 2-2' Fig. 1.

Fig. 3 is a horizontal sectional view at 3-3' Fig. 2.

Fig. 4 is a vertical sectional view at 4-4' 40 Fig. 2.

In the drawing like characters of reference indicate corresponding parts in the several figures.

1 represents a track rail spiked as is customary to the cross ties 2 and having a break or fracture 3 therein, such having occurred in the ordinary course of traffic and requiring repair.

50 My invention provides a clamp for quickly repairing such breaks in the rails and in actual practice two clamps are used together with the customary angle irons as at present employed for connecting the adjacent ends of rails. Each clamp is constructed in detail as now described.

4 is a base plate or shank having one end

provided with a fixed jaw 5 which extends outwardly from the shank and has the upper or gripping end 6 thereof turned inwardly and parallel with the shank and fitted with 60 an inwardly projecting stud 7 for a purpose later disclosed.

The other end of the shank is supplied with an elongated substantially rectangular slot 8. On the latter end of the shank I 65 mount slidably the base 9 of an adjustable jaw 10 which has the upper part thereof turned inwardly as shown at 11 and then upwardly to provide a gripping end 12 disposed in a vertical plane and opposing the 70 gripping end 6. The end 12 is also supplied with an inwardly extending stud 13 located directly opposing the stud 7.

14 is a jam screw having a squared head 15 and screw threaded through the end 12 75 of the jaw 10. 16 is an adjustable bolt fitted at the lower end with a squared head 17 and provided with a nut 18.

Here I wish it to be observed that the base of the adjustable jaw is connected slidably to the shank by means of two inturned L-shaped flanges 9' and 9" and that the head of the bolt 16 is received between the flanges which prevent it turning while the body of the bolt passes up through the slot 8 and through a receiving opening 19 provided in the base of said jaw. The nut 18 is applied on the upper end of the bolt. Obviously when the nut is loose one can shift the adjustable jaw in and out on the shank and he can, by tightening up the nut, secure the said jaw firmly in any adjusted position as the head of the bolt underlies the shank at the edges of the slot and is prevented from rotating by engagement with the 95 flanges 9' and 9".

When a broken rail is to be repaired two of these clamps are used together with a pair of angle bars 20 and 21, the angle bars of ordinary construction, being designed to fit 100 against the opposite sides of the rail as best shown in Fig. 2 and they are provided adjoining their ends with pairs of cross openings 22 and 23 which are adapted to receive the customary fastening bolts passed 105 through the web of the rail.

In making a temporary repair, these angle bars are placed on opposite sides of the rail at the break, taking the position as best shown in Fig. 1, it being here understood that the bars are positioned directly opposed. The sectionman, after having

placed the angle plates, puts one of my clamps at opposite sides of the break and tightens them up to hold the angle bars tightly in position against the web of the 5 broken rail.

As the manipulation of each clamp is the same the description of the manner in which one is applied will suffice.

To apply the clamp one removes the adjustable jaw from the shank by knocking out 10 the bolt 16. He then puts the shank and fixed jaw in place as shown in Fig. 2 with the shank under the base of the rail and the stud 7 of the fixed jaw entered in one or 15 other of the openings of one of the angle bars. The adjustable jaw is then placed back in position on the shank and forced up until the gripping end 12 is tight against the other of the angle bars, the stud 13 20 thereof being also entered in one or other of the openings 22 and 23.

After the two jaws have been initially drawn up as tightly as possible to jam the angle bars against the web of the rail the 25 nut 18 is tightened up to hold fast the adjustable jaw. The final tightening up is then made by turning the jam screw 14 which takes up any looseness there might be.

From the above it will be apparent that 30 by using these clamps a reliable temporary repair can be very quickly made and that afterward a final repair can be carried out

by drilling the web of the rail and fastening the angle bars to the rail by bolting in the ordinary manner.

What I claim as my invention is:—

1. The combination with the broken ends of a rail and angle bars disposed at opposite sides of the rail at the break, of a repair clamp presenting a shank passing beneath 40 the rail, a stationary jaw extending from the shank and engaging with one of the angle bars, a removable adjustable jaw engageable with the other of the angle bars, an adjusting screw carried by the adjustable jaw 45 and alining studs extending from the jaws.

2. A repair clamp comprising a shank provided at one end with an integral jaw, a second jaw slidably mounted on the shank and provided with inturned flanges embracing the sides of the shank, an adjustable bolt passing through said shank having the head thereof engaged between said flanges and thereby held against rotation, and a nut engaged with said bolt to lock the bolt 50 and sliding jaw in adjusted position on the shank.

Signed at Winnipeg, this 17th day of December, 1919.

WILLIAM ANDREW ROBERT ANGUS.

In the presence of—

GERALD S. ROXBURGH,
K. B. WAKEFIELD.
